UNITED STATES PATENT OFFICE.

NICHOLAS KIRCHNER, OF PHILADELPHIA, PENNSYLVANIA.

CABLE RAILWAY.

SPECIFICATION forming part of Letters Patent No. 355,826, dated January 11, 1887.

Application filed November 13, 1886. Serial No. 218,743. (No model.)

To all whom it may concern:

Be it known that I, NICHOLAS KIRCHNER, a citizen of the United States, and a resident of the city and county of Philadelphia and 5 State of Pennsylvania, have invented a new and useful Improvement in Cable Railways, of which the following is a specification.

The object of my invention is to furnish an elevated cable railway which will be capable 10 of attaining a high rate of speed, and which will be less costly and more convenient than the ordinary surface-cable systems.

In the accompanying drawings, in which similar letters of reference indicate similar 15 parts throughout the several views, Figure 1 is a side elevation of a car and trestle embodying my invention; Fig. 2, a section of Fig. 1 on line 1 2; Fig. 3, an end elevation of the rear wheels; Fig. 4, an end view of the upper end 20 of the front suspending-bar; Fig. 5, a side view of the same; Fig. 6, an end view of the grip and rod for operating it, and Fig. 7 a side view of the forward wheels.

A is the car. At the forward end is a rod, 25 B, which is securely fastened to the car, and the upper end of which is attached to a bar, C, which is carried by the forward truck. At the rear end is a rod, D, which passes up and is held by the axle of the rear truck.

30 The rails E are suspended in any suitable manner from a frame-work, F, which is erected in the street, and the car is suspended so as to clear the ground by from eighteen to twenty-four inches.

35 The upper end of the rod B is flattened out, as shown in Fig. 4, and to this flattened part the grip is fastened. The grip consists of two plates, G G', which are secured by pivots H H' to the flattened part of rod B.

40 I is the rod for operating the grip. Upon the top of this rod is a head or wedge, J, which, being pushed up or down, causes the grip to be opened or closed.

K is a lever for operating the grip-rod.

45 The grip-rod extends down, as shown in Figs. 1 and 2, and its lower end is bent to form an elbow, which is fastened at its end to a shaft, a. To this shaft the lever K is also fastened; hence by pushing lever K the wedge J is caused to descend, closing the grip, and by

pulling the lever the wedge is raised, opening the grip.

The brake consists of a beam, L, which is pivoted to the truck at b. There are two of these beams—one upon each side of the forward truck—and these beams are furnished with shoes c, which are adapted to bear upon each of the four wheels of the truck. Extending from one beam to the other is a rod, d, to which a rod, M, is attached. This rod extends down, and is bent at an angle at its lower end and secured to a shaft, a'. To this shaft is also secured a lever, N. By pushing this lever the 55 brake is put on. By pulling it it is taken off.

The rear truck consists of but two wheels, O 65 O'. To the center of their axle the rod D is secured. Upon each side of this rod are pulleys P P', over one of which the cable Q passes after leaving the grip. The rod D is extended above the pulleys P P', and its top is beveled 70 off, as shown in Fig. 3, so that the cable will always run in one or other of the pulleys. After the cable leaves these pulleys it falls upon one of the rollers R, of which there are a 75 number placed at regular intervals along the insides of both tracks E, and it is supported and guided by these rollers.

The cable is driven by machinery of any suitable description.

Having thus described my invention, I 80 claim—

1. A grip consisting of two plates, G G', pivoted to some suitable fixture carried by the trucks at H H', and being operated by a wedge, J, substantially as set forth. 85

2. The combination, with the wheels of the forward truck, of the beam L, pivoted to the truck-frames at b and furnished with shoes c and rods d and M, and devices, as described, for lowering or raising these rods, substantially 90 as set forth.

4. The combination of rod D with beveled top, as described, pulleys P P', and wheels O O', all substantially as and for the purposes set forth. 95

NICHOLAS KIRCHNER.

Witnesses:

OTIS EGAN,
CHAS. A. RUTTER.
